Assistant Examiner — Bryan N. Melvin

(57) **CLAIM**

The ornamental design for a battery box as shown and described.

DESCRIPTION

1.1: Perspective view;

1.2: Front view;

1.3: Back view;

1.4: Left view;

1.5: Right view;

1.6: Top view;

1.7: Bottom view;

1.8: Perspective view;

1.9: Enlarged view of portion labeled “**1.9**” in **1.1**; and

1.10: Unfolded state of usage view of **1.1**.

The dash-dash broken lines in the drawings depict the portions of the battery box that form no part of the claimed design.

The dot-dash broken lines in the drawings depict the boundaries of the enlarged views and form no part of the claimed design.

The label **1.9** in reproduction **1.1** forms no part of the claimed design.

1 Claim, 10 Drawing Sheets
